UNITED STATES PATENT OFFICE.

FREDERIC A. DELANO, OF CHICAGO, ILLINOIS.

LOCOMOTIVE-SUPERHEATER.

1,256,115.

Specification of Letters Patent. Patented Feb. 12, 1918.

Application filed June 5, 1916. Serial No. 771,906.

To all whom it may concern:

Be it known that I, FREDERIC A. DELANO, a citizen of the United States, residing at Chicago, in the county of Cook and State of Illinois, have invented certain new and useful Improvements in Locomotive-Superheaters, of which the following is a specification.

This invention relates to improvements in locomotive superheater. The object of this invention is to provide an improved form of superheater which will dispense with the plurality of pipe connections and at the same time afford a larger amount of superheated surface, while simplifying the cleaning of the apparatus.

Hitherto, in locomotive superheater construction, it has been the practice to provide comparatively small superheater pipes doubled back and forth in their respective flues and extending only partially through the same. This construction complicates cleaning of the flues and provides a plurality of threaded or headed connections which makes for greater possibility of leakage under high pressure. My device aims to eliminate these objections, as far as possible, by simplifying the construction and arrangement, and at the same time providing an equal or greater superheating surface. Other objects will be made apparent and set forth in the following specification and accompanying drawings, in which:

Figure 1 is a longitudinal vertical section through a boiler showing my improved form of superheater, located therein;

Fig. 2 is a transverse section along the line 2—2 of Fig. 1;

Fig. 3 is a similar section along the line 3—3 of Fig. 1.

Like numerals refer to like elements throughout the drawings.

10 designates generally the body of a locomotive having the usual fire box 11 at its rear end, the boiler 12 and smoke box 13. Fire tubes or flues 14 lead from the fire box 11 to the smoke box 13, through the boiler 12. The boiler 12 is provided with a steam dome 19^a at its upper end, in which terminates the intake end 15 of a duct 16, which leads to and is in communication with superheater manifold 17, comprising at its rear end the wet steam chamber 17^a and at its forward end the superheated steam chamber 17^b, these chambers being separated by the partition wall 17^c. The intake 15 is

provided with a well known valve construction having a depending stem 15^a actuated by bell crank 18, to which leads an operating rod 19, adapted to lead to the engine cab 60 (not shown).

Extending between the fire box 11 and smoke box 13, are superheater flues 20 relatively larger than the fire tubes of flues 14 and located in this construction, in two rows, 65 35 as shown in Fig. 3.

Depending from and secured to the manifold 17, in communication with the wet steam chamber 17^a, is a series of elbows 21, terminating in the flanged ends 21^a, as shown 70 in Fig. 1. Similarly, elbow members 22 depend from and are in communication with the superheated steam chamber 17^b of manifold 17. These elbow members 22 depend 75 below the members 21 and are similarly provided with flanged ends 22^a. Leading rearwardly through the upper series of superheater flues 20, are the superheater tubes 23 located one in each of said flues and normally spaced therefrom by the spacing members 80 24 which are constructed to permit circulation 75 of the heating gases around the tubes 23. The forward ends of tubes 23 are provided with the ball portion 23^a secured to the flanged ends 21^a of the respective elbow 85 members 21, and adapted to be retained in non-leaking position with respect thereto, by the flanges 23^b, and coating bolts 24^a. This is a well known form of ball and socket joint 90 and needs no further description here. The tubes 23 project into the fire box 11 and are secured by a welded sleeve joint or similar means at points 23^c to a curved or bent elbow 25.

By spacing the corresponding flues 20 of 95 the upper and lower set a sufficient distance apart, the bent elbow 25, which may be formed separately if so desired, may be formed of comparatively gentle curve in contradistinction to the short bend required 100 in the ordinary form of superheater construction where small tubes are doubled in a single flue. Where the bent elbow 25 is located in the fire box 11, as shown, it is 105 advantageous to protect the same from the direct action of the fire flame and I coat the same with one or more layers 26, of fire-proof material such as asbestos, which will prevent the oxidizing of the metal superheater tubes when in contact with the 110 flame. At the forward end of the lower portion of tubes 23 they are secured by

ball connection to flanged ends 22^a and elbow members 22, similarly to the connections at flanged ends 21^a of the elbow members 21. Flanged outlet apertures 17^d are 5 provided in the manifold 17 and superheated steam ducts 27 may be secured thereto to lead therefrom to the steam chest. It will be apparent that steam may be admitted to the wet steam chamber 17^a through the 10 intake duct 16, passage therethrough being regulated by the valve in intake 15. From the wet steam chamber 17^a it will pass through the superheater tubes 23 and will be returned to superheated steam chamber 17^b 15 of manifold 17; from hence it will be supplied to the steam chests and respective cylinders.

While I have described and shown my invention with more or less particularity, I 20 do not desire to be restricted to the form shown and described, beyond the scope of the appended claims.

What I claim is:—

1. In a locomotive, a fire box, a boiler, a 25 smoke box, flues in said boiler leading from said fire box to said smoke box, a manifold comprising a wet steam chamber and a superheated steam chamber, a series of elbows depending from said wet steam chamber, a second series of elbows depending from said superheated steam chamber, superheating tubes each detachably connected to an elbow of said first-named series and leading from one of said flues to said fire 30 box, each of said superheating flues returning from said fire box through another of said flues and being detachably connected to an elbow of said second-named series, and fire proof material for covering said superheating tubes in said fire box.
2. In a locomotive, a boiler having a plu 35

rality of flues extending therethrough, a manifold comprising a wet steam chamber and a superheated steam chamber, a series of duct members leading from said wet steam chamber adjacent one end of said boiler, a second series of duct members leading from said superheated steam chamber, and superheating tubes each detachably connected to a duct member of said first-named 45 series and leading through one of said flues to the other end of said boiler, each of said superheating tubes returning from the other end of said boiler through another of said flues and being detachably connected to an 50 elbow of said second-named series.

3. In a locomotive, a fire box, a boiler and a smoke box, flues in said boiler leading from said fire box to said smoke box, a manifold comprising a wet steam chamber 60 and a superheated steam chamber, a series of elbows depending from said wet steam chamber, a second series of elbows depending from said superheated steam chamber, and superheating tubes, each detachably 65 connected to an elbow of said first named series and leading through one of said flues to said fire box, each of said superheating tubes returning from said fire box through another of said flues and being detachably 70 connected to an elbow of said second named series, said tubes being formed to permit withdrawal thereof from said flues toward said fire box when detached from said 75 elbows.

In testimony whereof, I have subscribed my name.

FREDERIC A. DELANO.
